HEADBOARD FOR A BEDSTEAD OR SIMILAR ARTICLE

Raul Z. Zamora, 562 University Ave.,
San Jose, Calif. 95110

Filed June 19, 1970, Ser. No. 23,571

Term of patent 14 years

Int. Cl. D6—01

U.S. Cl. D5—4

FIG. 1

FIG. 2

FIG. 1 is a front perspective view of a headboard for a bedstead or similar article, showing my new design; and FIG. 2 is a front elevational view thereof.

The rear not shown is substantially plain.

The strings of dots represent a beaded chain.

I claim:

The ornamental design for a headboard for a bedstead or similar article, substantially as shown and described.
